UNITED STATES PATENT OFFICE.

FERDINAND B. ALMY, OF MELROSE, MASSACHUSETTS

LACING-HOLDER FOR WEARING-APPAREL.

No. 888,454.

Specification of Letters Patent.

Patented May 26, 1908.

Application filed June 17, 1907. Serial No. 379,348.

To all whom it may concern:

Be it known that I, FERDINAND B. ALMY, a citizen of the United States, residing at Melrose, county of Middlesex, and State of Massachusetts, have invented an Improvement in Lacing-Holders for Wearing-Apparel, of which the following description, in connection with the accompanying drawing, is a specification, like letters on the drawing representing like parts.

This invention has for its object the production of novel lacing holders adapted to be engaged with any usual eyelet, the holders receiving the lacing and being detachable from the eyelet when the lacing is to be manipulated to unlace a boot, glove or other article of wearing apparel. The holders when disengaged from the eyelet retaining themselves on the lacing.

My novel holders are so constructed that a skirt can not catch on the same as with usual lacing hooks having hollow shanks upset in a shoe top and herein my novel holders, among other uses, are especially desirable for application in connection with ladies' boots and shoes.

Figure 1 shows a ladies' boot having a lacing supplied with my novel holders; Fig. 2 shows a lacing with a series of holders positioned thereon; Fig. 3 is an enlarged section on the line $x-x$, Fig. 1; Fig. 4 is an underside view of the holder; Fig. 5 shows the blank from which a holder may be made; Fig. 6 is a section on the line $x'-x'$, Fig. 4. Fig. 7 is a side view of the holder; Fig. 8 is a section similar to Fig. 3 showing the holder applied to the edge of a glove; Fig. 9 is a view similar to Fig. 4, showing a modified construction.

Referring to the drawing A represents a lady's boot with its top A' provided with a series of eyelets a set in the top slightly back from the usual edges a'.

My holders to be described may be applied to advantage to a boot or shoe or any wearing apparel or other article having openings or eyelets.

In manufacturing my holders I cut from suitable sheet metal a blank B of substantially the shape shown in Fig. 5, it having a wide end b and a shank b', said wide end, in the preferred form herein illustrated, being of crescent shape to leave two horns 2, 2. The blank shown is subjected to the action of dies that give a concavo convex shape, see Figs. 3 and 6, to the wide end in the direction of

its length and width, as shown in Figs. 3 and 6, to constitute the head B of the holder, the dies causing the outer edge 30 of the blank to be turned from the position Fig. 5 into the position Figs. 3, 4 and 6, to constitute a foot b^2 to contact with the material of the article in which the eyelet is set, said foot substantially surrounding the eyelet, as best shown in Figs. 1 and 3, leaving exposed only a small portion of each eyelet nearest the edge a'. 65

In the manufacture of a holder from a blank B the shank b' is bent at 3 and a portion 4 thereof is carried forwardly under the head B, see Fig. 3, and then again bent, as shown at 5, to form a shank 6 of a length to 70 extend substantially through the eyelet a, the shank being again bent, as at 7, to form a tongue t of sufficient length to reach under and across one side of the set eyelet, as shown in Fig. 3, the tip of the tongue projecting beneath the foot b^2 . The bend 5 and the upper side of the part 4 of the shank between the bends 3 and 5 is so located with relation to the curved parts 8 of the horns 2 as to leave a sort of eye or space 20 shown best in Fig. 7 75 into which is drawn the lacing D, said space being so proportioned to the size of the lacing in cross section as to hold the lacing with sufficient friction to prevent the sliding of the holders on the lacing after they have been 80 once correctly located or spaced on the lacing, except by engaging the holders by hand and exerting a force beyond that to which the holders will be subjected in regular use.

Fig. 1 shows the boot laced and the lacing 90 tied and in such condition the lacing by drawing on the holder within the bend 3 at a point above the top of the eyelet, causes the foot b^2 to be held seated onto the material surrounding the eyelet and the tongue t underlying the eyelet prevents the holder from leaving the eyelet. Now when the lacing is untied and pulled away from the edge a' and slightly away from the material containing the eyelets, the holders fall readily out of the 100 eyelets occupied by them, leaving all the eyelets free, the holders retaining their position on the lacing, as shown by Fig. 2, and with the finger the lacing which is led through the several eyelets next the vamp of the boot 105 may be loosened if necessary to enable the boot top to be opened that the foot may be removed therefrom.

To lace the boot it is only necessary to insert the tongue of each holder of a series of 110

holders one after another in the eyelet hole near one edge a' and then in an eyelet hole back of the opposite edge a' , the eyelet holes entered by the holders carried by one lacing 5 occupying different positions in planes at right angles to the edge a' or not being in the same plane crossing the shoe.

The eyelets shown are of rigid material, such, for instance, as metal or celluloid, yet 10 my invention is not limited to the use of a metal eyelet as in some classes of wearing apparel the eyelets might be made of thread and be made stitch after stitch.

My holders may be used as a glove fastener 15 and in such event a tongue or under flap should be provided against which the tongues of the holders may rest when holding the glove closed.

In Fig. 1 the boot has a leather tongue e 20 against which the tongues of the holder contact. Fig. 8 shows an under flap e' such as I may use with a glove, a corset, a waist, or any other gaping part of wearing apparel that it is desired may be laced, and which it 25 is desired may be quickly undone so that the lacing need not be withdrawn through an eyelet hole.

It sometimes happens that the eyelets a 30 vary somewhat in size, and to permit the holder to be used with different sizes of eyelets I will make the tongue t and shank 6 bifurcated, as shown in Fig. 9, with which construction the sides of the tongue and shank will spring together to permit them to 35 be inserted through smaller eyelets.

Having fully described my invention, what I claim as new and desire to secure by Letters Patent is:—

1. A holder having a head and shank, the 40 shank being bent to form a space between itself and said head at one side of the latter for the reception of a lacing and having a second bend to present a tongue extended under and toward the opposite side of the head.

2. A holder having a head provided at its 45 under side with a foot and having a depending shank terminating in a tongue extended laterally under and toward the opposite side of said head, the tip of the tongue projecting beneath the foot.

3. A holder having a head provided with 50 horns and with a shank and tongue curved under said head leaving a space for the re-

ception of a lacing between said shank and head.

4. A holder presenting a head concavo-convex in the direction of its width and length, and a connected shank terminating in a tongue occupying a position under said head, the tongue being substantially parallel 60 to the plane of the bottom of the head.

5. A lacing having spaced on the same a series of holders comprising heads having tongues crossing said heads at their under sides.

6. An article of apparel having annular eyelets near its opposed edges, combined with means for holding said edges closed comprising lacings and connected holders, the holders having shanks to be thrust 70 through said eyelets, the shanks pointing backwardly from the edges to be closed and extending beneath the material to which the eyelets are attached.

7. An article of apparel having eyelets 75 near its opposed edges, combined with means for holding said edges closed comprising lacings and connected holders, the holders having shanks to be thrust through said eyelets, the shanks pointing backwardly from the 80 edges to be closed and the heads of the holders being concaved to substantially cover the eyelet.

8. An article of wearing apparel having eyelets at its opposed edges, and an under 85 flap, combined with a lacing provided with a series of holders comprising heads and shanks and tongues underlying said heads, the tongues being adapted to be passed through the eyelets and occupy a position 90 between the under sides of the eyelets and the upper side of the under flap.

9. A lacing holder having a head concaved at its under side and comprising a foot to bear on the material with which said 95 holder coacts, and a shank and tongue bent under said head and adapted to be thrust through said material.

In testimony whereof, I have signed my name to this specification, in the presence of 100 two subscribing witnesses.

FERDINAND B. ALMY.
